UNITED STATES PATENT OFFICE.

ARTHUR W. POPE, JR., OF WAUKESHA, WISCONSIN, ASSIGNEE TO WAUKESHA MOTOR COMPANY, OF WAUKESHA, WISCONSIN, A CORPORATION OF WISCONSIN.

COOLING SYSTEM.

Application filed August 25, 1926. Serial No. 131,377.

My invention relates to cooling systems for internal combustion engines. In prior cooling systems ordinarily used, when the engine is started up with the radiator or water tank 5 full of cold water, a very long time is required to bring the water up to the proper operating temperature for the engine, and when this temperature is finally reached it will not remain constant but will continue to rise until 10 the boiling temperature is reached, whereafter all of the steam formed in the engine will escape to the atmosphere and be lost, and steam pockets under high pressure will be formed in the engine jacket. As a result, 15 the engine is always either too hot or too cold, and after it becomes heated up there is a great loss of water in the form of steam.

The object of my invention is to provide 20 an arrangement in which the water in the engine jacket is, in a few moments after the engine is started, brought to the boiling or steam temperature, and such operating temperature is constantly maintained until the 25 engine is stopped, independently of the temperature of the water in the radiator, condenser or water tank, and independently of the load on the engine, and without requiring either a cooling fan or a water circulating pump.

30 Structure and apparatus for carrying out my invention is shown on the drawings in which:

Figure 1 diagrammatically represents an 35 internal combustion engine and water tank and condenser mechanism; and

Fig. 2 shows a modified arrangement.

The engine E shown has the water jacket 10 around its cylinders 11. The tank 12 serves 40 to hold water supply, and in the top of this tank is inserted a shell 13 spaced from the tank side to form a steam chamber or condenser 14, this condenser being closed at the top but open at its lower end to the water tank. The top of the tank is covered by a 45 hood 15 having the steam vent 16. The steam outlet pipe 17 from the engine water jacket connects with the condenser at the top thereof, and the water supply pipe 18 extends from the lower part of the water tank to the lower end of the water jacket.

50 The normal level of the water in the water tank is indicated by the line $a-a$, this level being below the connection of the steam pipe 17 with the condenser 14. When the engine is started, there will therefore be no circulation

of water to the jacket 10 and consequently the water in the jacket is quickly raised to the boiling or steam point. As steam is formed in the jacket, it rises in the outlet pipe 17 and flows into the condenser 14 above the 55 water therein. As the amount of steam increases, it will exert pressure on the water in the condenser and will force the water downwardly, the water level then rising in the tank section within the shell 13. The steam 60 pressure required to accomplish this will at any time be equal to the head of water within the shell 13 above the water level in the condenser. As soon as the water in the condenser is forced down to the lower end thereof, the 65 equilibrium point will be reached and thereafter any additional steam pressure will cause the steam to escape around the lower edge of the shell 13 and upwardly through the space within the shell and the water therein, and 70 then through the hood 15 and out of the vent 16. In the travel of the steam from the engine to the vent, there is considerable opportunity for condensation, first in the outlet pipe 17, then by contact with the water cooled 75 walls of the condenser, then by contact with the water in the water tank and finally by contact with the hood 15. If this combined condenser capacity is not sufficient to condense 80 all of the steam, any surplus steam will pass 85 quietly out through the vent without interfering with the operation of the system other than the loss of the corresponding amount of water. The operation of the system will not be influenced by loss of water until the level 90 in the water tank falls below the lower end of the condenser.

In my arrangement, the minimum for low 95 level of water in the cylinder jacket is determined by the level of the lower end of the condenser. If the steam flow were not restricted in the jacket and the outlet pipe, the low level in the jacket or outlet pipe would be coincident with the level of the lower end of the condenser, as the steam above the water 100 in the steam chamber and outlet pipe will tend to force the water down equally. In the arrangement shown, the line $b-b$ represents the desired low water level in the water jacket, and on account of the restriction or 105 resistance to steam flow and consequent development of steam pressure in the jacket, the lower end of the condenser will have to be located a corresponding distance above the level $b-b$ to the level $c-c$ in the arrange- 110

ment shown. The distance between the level $b-b$ and $c-c$ is the head of water equal to the pressure required to overcome the friction to steam flow and to establish the minimum or low level of water in the cylinder jacket.

In order to break the vacuum which would be formed in the condenser after the engine is stopped and the system is allowed to cool, I provide a vent 19 shown connected with the outlet pipe 17 and controlled by a check valve 20. This valve prevents the outflow of steam or water but permits inflow of air to prevent the formation of vacuum.

Fig. 2 illustrates an arrangement in which a conventional form of condenser 21 is used and a water tank 22 associated therewith. The steam outlet pipe 17 from the engine water jacket connects with the upper end 20 of the condenser while the lower end of the condenser is connected through pipe 23 with the bottom of the water tank 22. The steam generated in the engine jacket flows into the condenser or above the water therein and 25 forces the water downwardly and through connection 23 into the tank or reservoir 22 until the water in the condenser reaches the level of the connection 23 whereafter the surplus steam will flow into and through the 30 water in the tank to the exterior through the open top of the tank or through a vent.

In the arrangement of Fig. 1, the steam flowing through the condenser is condensed by being subjected to the shell 13 which is 35 water cooled, while in the arrangement of Fig. 2 the condensation of steam flowing through the condenser is caused by draft through the condenser structure resulting during travel of the vehicle or generated by 40 a fan. In either structure, there is no direct escape for the steam to the atmosphere after passing through the condenser, except through the water in the water tank or reservoir, which tank or reservoir, besides furnishing a large reserve supply of water, 45 serves also as an overload condenser so that there will be very little flow of steam to the steam vent and consequently very small loss of water.

In the arrangement of Fig. 2, as in the arrangement of Fig. 1, the level $c-c$ at the bottom of the condenser is sufficiently above the desired low water level $b-b$ in the jacket so that such low level will not be exceeded.

I thus produce a very simple cooling system for internal combustion engines by which the water in the engine jacket will be quickly raised to boiling or steam generating temperature and will have such temperature constantly maintained independently of the load on the engine or the temperature of the water in the condenser or water tank or at other parts of the system. An engine thus served will give much more uniform, reliable and efficient service. As the loss of water is re-

duced to a minimum, the system requires very little care or attention.

I claim:

1. In a steam cooling system, the combination with the water jacket of an internal combustion engine, of a water tank, and a condenser, a steam connection from the water jacket to the top of the condenser, a water connection from the lower part of the water tank to the water jacket, and a connection 75 between the lower part of the condenser and the water tank, the water in said tank being in contact with the side walls of said condenser.

2. In a steam cooling system, the combination with the water jacket of an internal combustion engine, of a water tank, a steam receiving space within the tank closed at its upper end and open at its lower end to the tank, a steam duct connecting said water 85 jacket with said steam space at a point above the normal level of water in said steam space, and a water connection to the water jacket from the water tank at a point below said steam space.

3. In a cooling system for internal combustion engines, a water jacket having a steam outlet from its upper end, a condenser for receiving the steam, a water tank for water supply for cooling said condenser and for 95 replenishing said jacket, and means for causing steam to flow from the condenser through the water in the tank.

4. In a steam cooling system for internal combustion engines, the combination with 100 the engine water jacket, of a condenser, and a water tank, the condenser at its lower end being connected with said water tank below the water level in the tank whereby any steam uncondensed in said condenser will flow 105 through the water in the tank to be condensed, the upper end of said condenser being connected with the water jacket to receive the steam therefrom as it is generated, a connection from the lower part of said water 110 jacket to said water tank for receiving water supply, the connection of said condenser with said water tank being a distance above the water jacket whereby to create a water head 115 for offsetting the resistance to the steam flow and for maintaining the water level in said water jacket.

5. In a steam cooling system for internal combustion engines, the combination with the engine water jacket, of a water reservoir 120 and a condenser, there being a connection between the condenser and reservoir below the normal water level in said reservoir for the inter-flow of water between said condenser and reservoir, a connection for the flow of 125 steam from said water jacket to said condenser above the water level therein, a water return connection from said reservoir to said jacket and an air vent for said reservoir.

6. In a steam cooling system for internal 130

combustion engines, the combination with the engine water jacket of a condenser and a water reservoir, a steam connection from the water jacket to the upper part of the condenser, a connection from the lower part of said condenser to said reservoir at a point below the water level in the reservoir whereby steam flow from such condenser must pass through the water in said reservoir, said res-

ervoir having an air vent, a water return connection from the reservoir to said jacket, said condenser being within said reservoir to be engaged and cooled by the water in the reservoir.

In witness whereof, I hereunto subscribe my name this 20th day of August, 1926.

ARTHUR W. POPE, JR.
